(No Model.)

J. B. MARTEL.

MECHANICAL MOVEMENT.

No. 293,483.

Patented Feb. 12, 1884.

UNITED STATES PATENT OFFICE.

JEAN BAPTISTE MARTEL, OF NEWARK, NEW JERSEY.

MECHANICAL MOVEMENT.

SPECIFICATION forming part of Letters Patent No. 293,483, dated February 12, 1884.

Application filed November 13, 1883. (No model.)

To all whom it may concern:

Be it known that I, JEAN B. MARTEL, a citizen of the United States, residing at Newark, in the county of Essex and State of New Jersey, have invented new and useful Improvements in Mechanical Movements, of which the following is a specification.

This invention relates to mechanical movements whereby a powerful motion can be transmitted from a revolving shaft. The precise nature of my invention is pointed out in the following specification, and illustrated in the accompanying drawings, in which—

Figure 1 represents a side view. Fig. 2 is an end view, partly in section.

Similar letters indicate corresponding parts.

In the drawings, the letter A designates the main shaft, which has its bearings in a suitable frame, B, and to which a revolving motion is imparted by any suitable motor. On the shaft A is mounted a fly-wheel, C, and upon the circumference of this fly-wheel rests a friction-pulley, D, which is mounted on a shaft, E, that has its bearings in arms F, which swing on a rod, G, mounted in the upper part of the frame B. The friction-pulley is covered with leather, india-rubber, or other suitable material, and it is held in contact with the circumference of the fly-wheel C by a spring, H, which is hitched to the shaft E; or two springs may be used, one being hitched to each of the arms F. On the shaft E is also mounted a fly-wheel, I, the weight of which serves to depress the friction-pulley D upon the circumference of the fly-wheel C. On the ends of the shaft E are mounted pulleys J J, from which a rapid motion can be transmitted to a line-shaft. When the main shaft A is revolved by a crank, Q, or its equivalent, a very rapid motion is imparted to the shaft E, and since the friction-pulley D is held down upon the circumference of the fly-wheel C by the weight of the fly-wheel I, and by the spring or springs H, said friction-pulley is not liable to slip, and the motion transmitted from the pulleys J J is not only very rapid, but also powerful.

On the shaft A are mounted two drums, K L. The drum K bears upon a drum, K', which, in its turn, bears upon a drum, K'', so that both the drums K' K'' are caused to re-

volve, and from the shafts on which these drums are mounted motion can be transmitted to line-shafts. The drums K K' K'' may, however, be geared together by cog-wheels. 55 The drum L bears upon a drum, L', which, in its turn, bears upon a drum, L'', and on the shaft of the drum L' is secured a crank, l', which connects by a spring, l, with a crank, l'', mounted on the end of the shaft of the 60 drum L'', so that by the action of this spring these two drums are held in close contact with each other, and a powerful motion can be transmitted from their shafts to one or more line-shafts. The drums L L' L'' may, however, be 65 geared together by suitable cog-wheels. The drum L is also geared together with a drum, M, which is geared together with a drum, N, and on the shaft of the drum M is mounted a circular saw, S, while on the shaft of the drum 70 N is mounted a feed-wheel, W, so that my machine can be used for cutting up boards; but it is evident that it can be applied to a variety of other uses; and it can be driven by hand, steam, water, or any other suitable 75 power.

What I claim as new, and desire to secure by Letters Patent, is—

1. The combination, with the shaft A, and with the fly-wheel C, mounted on said shaft, 80 of the friction-pulley D, the swinging arms F, the secondary fly-wheel I, and the spring or springs H, substantially as shown and described.

2. The combination, with the shaft A, the 85 fly-wheel C, the friction-pulley D, the swinging arms F, and the secondary fly-wheel I, of the drums K K' K'', substantially as shown and described.

3. The combination, with the shaft A, the 90 fly-wheel C, the friction-pulley D, the swinging arms F, and the secondary fly-wheel I, of the drums L L' L'', the cranks l l'', and the spring l, substantially as shown and described.

In testimony whereof I have hereunto set my 95 hand and seal in the presence of two subscribing witnesses.

JEAN BAPTISTE MARTEL. [I. S.]
